UNITED STATES PATENT OFFICE

PARIS R. FORMAN, OF RAHWAY, NEW JERSEY, ASSIGNOR TO NATIONAL PNEUMATIC COMPANY, OF NEW YORK, N. Y., A CORPORATION OF WEST VIRGINIA

TREADLE SWITCH STRUCTURE

Application filed November 19, 1927. Serial No. 234,538.

This invention relates broadly to electric treadle plates for use on vehicles such as street cars, subways, elevated lines and the like.

5 One of the objects of this invention is the provision of an improved form of treadle structure for use on vehicles in which the door opening and closing operations are at least partially under the control of a treadle structure mounted in the plate of the vehicle adjacent the doors to be operated.

A further object of this invention is the provision of a treadle structure either of the pivoted type or the full floating type.

15 A further object of this invention is the provision of a treadle device of either of the above types adapted for use in vehicles having relatively thin platforms so that the depth of the treadle plate must be at a minimum in order to be accommodated therein.

A further object of this invention is the provision of an improved treadle construction which will be sufficiently sensitive so as to operate at the proper time and which will, 25 at the same time, provide a rugged construction.

A still further object of this invention is the provision of a unitary structure for detachable connection to a treadle plate including resilient means for supporting the treadle in raised position and switch structure arranged to be operated upon depression of the treadle plate.

30 A further object of this invention is the provision of treadle plate construction embodying the above features which is relatively simple in construction and employs as few parts as possible.

These and many other objects are secured 40 by the construction about to be described.

This invention resides substantially in the combination, construction, arrangement and relative location of parts as will appear more fully in the following description when taken 45 in connection with the accompanying drawings.

Referring to the drawings which are given for purposes of illustration rather than in a limiting sense,

50 Figure 1 is a top plan view of the device

of this invention with a portion of the treadle plate broken away,

Figure 2 is an enlarged plan view of the resilient means employed for supporting the treadle in raised position,

55 Figure 3 is a vertical enlarged cross-sectional view of this supporting means taken on the line 3-3 of Figure 1,

Figure 4 is an enlarged vertical cross-sectional view of the switch structure taken on the line 4-4 of Figure 1.

60 Figures 5 and 6 are enlarged cross-sectional views of the device employed for guiding the full floating type of treadle in its movement and maintaining it in proper position.

65 Figure 7 is a perspective view of the full floating type of treadle showing a bottom view thereof, and

70 Figure 8 is an enlarged plan view of the resilient supporting means and switch structure looking at it from the bottom with the duplicate parts broken away.

75 There are several types of vehicles now used on street cars, subway, elevated and the like lines particularly of the one-man control type in which the opening and closing operation of the doors is at least partially under the control of a treadle plate in the floor of the vehicle and adjacent the doors.

80 In some constructions employing these features after the motorman has applied the brakes and the car has come to a stop the doors automatically open if a passenger is standing in front thereof on the treadle plate.

85 Upon the clearing of the passage ways in the vehicle so that there is no one standing on the treadle plate the doors automatically close.

90 The treadle plate structure itself includes some form of depressible plate supported in the platform of the vehicle in front of the doors so that a passenger stepping thereon will cause it to move downwardly a short distance to effect the operation of any device 95 attached thereto as, for instance in the case of this invention, electric switches. There are two general types of treadle plates, namely, the type in which one end is mounted on pivots and the other end maintained in

slightly raised position by some form of spring structure and a full floating type in which the treadle is supported at its four corners by means of some spring construction.

5 This invention involves improvements in construction of these two types of treadle plates. To more clearly understand the features of the present construction reference is made to the drawings in which 1 comprises 10 angle irons which are securely attached to the floor of the vehicle to form an enclosing and protecting frame-work for an opening cut in the floor of the vehicle in front of the doors. The attachment of these angle irons to the 15 floor 2' of the vehicle will readily be apparent by referring to Figures 5 and 6. In the pivoted type of construction as illustrated in Figure 1 the treadle 2 is pivotally mounted on the rod 3 so as to lie within the framed 20 opening formed by the angle irons 1 so that the edge marked A is adjacent the doors. The front edge A of the treadle is in its normal inoperative position raised slightly and is adapted to be depressed downwardly upon 25 the presence of sufficient weight such as that of a passenger on the treadle.

A container 4 is mounted under the treadle plate within the depending flanges of the treadle plate and has mounted therein an enclosed box comprising the portions 8 and 9 which are held therein by means of the latch construction 5. All the parts within the box 9 and cover 8 comprise a unitary structure for detachable mounting on the treadle plate. 35 An armoured cable 6 encloses the wires leading to the switch structure. As is apparent from Figure 1 the container 8-9 includes three separate compartments. One compartment contains the wires leading from the cable 6 which include the wire 12 grounded to the container, the wire 13 connected to the contact 14 in the next compartment, the wire 15 connecting the two contact plates 16 and 17 in the next compartment and the return wire 40 18 connected to the contact plate 16. The next compartment also includes the spring arms 19 and 20 which are mounted on the plates 16 and 17 respectively. The insulating buttons 21 are supported on the spring 45 arms 19 and 20 and project through the cover 50 8 as may more clearly be seen in Figures 4 and 7. The middle compartment may be lined if desired with a suitable insulating material 22 and the terminals of wires 15, 18 and 13 are insulated also from the container 8-9. Mounted within the last compartment at each end thereof are the U-shaped 55 pieces 23. The structure at each end of this compartment is exactly the same as shown in Figure 1 and it is not necessary, therefore, to duplicate it at the other end. Supported in notches in the U-shaped piece 23 (Fig. 3) is a short pin 24 on which is pivotally mounted the levers 25 which have at one end the projection 25' which also extends through an

opening in the cover 8. Another U-shaped member 26 supported in a notch in the levers 25 is provided having a pin 27 mounted in eyelets at the ends thereof. A rod 28 is secured to the pin 27 and passes through the bracket 29 and is encircled by a spiral spring 30 which is held thereon by means of the wing nut 31. Supported under the treadle and attached to the angle irons 1 is the plate 7 arranged so that the unitary 75 switch and resilient supporting structure is mounted between it and the treadle plate. This provides a support against which the buttons 21 and the ends 25' of the levers 25 project.

80 The full floating type of treadle shown in Figure 7 is substantially the same as far as the switch and supporting structure is involved with the exception that two of these units are mounted under the treadle so that the treadle is supported approximately at its four corners on the projections 25' of the levers 25. The treadle is mounted in the frame-work formed by the angle irons 1 which are in this case notched as shown in Figures 5 and 6 to receive the brackets 32 attached to the treadle plate for guiding the movement of the treadle and holding it in proper position. The only difference between Figures 5 and 6 is that in the former the treadle 2 is shown in raised position and in the latter the treadle 2 is shown in depressed position.

85 The operation of this construction is as follows. Referring first to the pivoted type of treadle when a weight is pressed thereupon as when a passenger steps on the treadle plate, the treadle is depressed against the resistance of springs 30. The weight of the passenger on the treadle plate causing the ends 25' of the levers 25 to move into the box 8-9 (Figure 3) pulling the members 26, 27, 28 and 31 to the left and compressing the spring 30. Coincidentally with the movement of the levers 25 the buttons 21 which project the same distance from the box 8-9 as the ends 25' are moved into the box causing the spring arms 19 and 20 to contact with the plate 14 thus completing the circuit of any device connected to the wires 13 and 18. In the usual systems now used these wires 105 would run to the well known type of electro-magnetic valve used on pneumatic door engines. It is, of course, to be understood that the pressures on the spring 30 may be so adjusted that the treadle plate will operate 110 under the correct pressures without being over sensitive.

115 In the full floating type of treadle plate the treadle is supported at its four corners on the projections 25' and is thus adapted to be operated by the presence of a passenger on any part thereof. This construction is found to be more sensitive to weights imposed at any point thereon than the pivoted type. As 120 is clear in Figure 1 the switches in each box 125 130

are connected in parallel and in the full floating type of treadle, the wires from each of the boxes are connected in parallel so that on the operation of any one of the four switches the 5 magnet valve which controls the supply and exhaust of fluid pressure to the door engine would be energized. In both types of treadle as is apparent when the weight is removed from the treadle the springs 30 will cause the 10 levers 25 to return them to raised normal position.

It will be apparent from the foregoing description that I have devised an exceedingly novel and simple treadle plate construction adapted for use in vehicles in which 15 there is not much space in the car platforms for switch devices. I am well aware that numerous changes in the details of construction and relative association of parts will readily 20 occur to those skilled in the art and I do not propose, therefore, to be limited to the exact features of construction shown for purposes of illustration but rather to the scope of my invention as I define it in the appended 25 claims.

What I seek to secure by United States Letters Patent is:

1. In a treadle construction the combination with a pivoted treadle plate of a unitary 30 structure solely supported on said treadle including a switch and means for maintaining said treadle in raised position whereby said switch is open.

2. In a structure as described the combination 35 with a treadle plate of means completely mounted thereon for supporting the treadle plate in raised position.

3. In a structure as described the combination 40 with a treadle plate of means completely mounted thereon for supporting the treadle plate in raised position and means also completely on said treadle plate which is rendered inoperative when said supporting means maintains said treadle plate in raised position.

4. In a structure as described the combination 45 with a treadle plate of a unitary detachable structure completely supported on to said plate including resilient means for supporting said treadle plate in raised position and switch structure arranged to be operated when the treadle plate is depressed.

5. In a construction as described the combination 55 with a depressible treadle plate of means attached solely thereto for supporting said plate at a plurality of points in raised position and a plurality of switches also attached solely to said treadle plate in a manner as to be operated upon depression of the treadle plate.

6. In a treadle plate assemblage the combination 60 with a pivoted treadle plate of means supported thereon including spring controlled levers for supporting the treadle in raised position and a plurality of switches ar-

ranged to be operated when the treadle plate is depressed.

7. In a treadle plate assemblage the combination 70 with a treadle plate of a plurality of unitary devices attached solely to the under surface of said treadle plate including resilient means for supporting the treadle in raised position and a plurality of switches adapted to be closed upon depression of said treadle plate.

8. In a treadle plate assemblage the combination 75 with a depressible treadle plate of a plurality of pivoted levers arranged for movement against the resistance of a spring, said levers being mounted under said treadle plate and a plurality of switches also mounted under said treadle plate and arranged to be operated upon the depression of said treadle plate.

9. In a unitary structure for treadle plates 80 as described the combination with a closed container having a plurality of compartments of a plurality of pivoted levers having their ends extending through one wall of said container, springs for resisting the movement of said levers when pressure is applied to their projecting ends and switches mounted within one of said compartments having operating means also projecting through one wall of said container so that they may be 85 operated externally of said container.

10. The combination with a support having 90 an opening therein of a treadle plate mounted in said opening, a plurality of levers pivotally mounted on said treadle for supporting it and a plurality of switches arranged to be operated upon depression of said treadle, said levers and switches cooperating with said support.

11. In a treadle plate assemblage, the combination 95 with a depressible plate of a plurality of levers pivotally supported under said plate and arranged to be rotated upon depression of said plate and adjustable resilient means for resisting the rotation of said levers whereby the plate is normally maintained in raised position.

12. In a treadle plate assemblage, the combination 100 with a depressible plate of a plurality of levers pivotally supported under said plate and arranged to be rotated upon depression of said plate and adjustable resilient means for resisting the rotation of said levers whereby the plate is normally maintained in raised position and a plurality of switches arranged to be operated upon the depression of said plate.

In testimony whereof I have hereunto set my hand on this 16th day of November, A. D., 1927.

PARIS R. FORMAN.
